CLAIM

The ornamental design for an extension module for an instrument container for conditioning and refrigerating units, as shown.

DESCRIPTION

FIG. 1 is a perspective view of an extension module for an instrument container for conditioning and refrigerating units;

FIG. 2 is a front view of the extension module of FIG. 1;

FIG. 3 is a rear view of the extension module of FIG. 1;

FIG. 4 is a top view of the extension module of FIG. 1;

FIG. 5 is a bottom view of the extension module of FIG. 1;

FIG. 6 is a first side view of the extension module of FIG. 1; and,

FIG. 7 is a second side view of the extension module of FIG. 1.
